CLAIM

I claim the ornamental design for a MIFI device, as shown and described.

DESCRIPTION

FIG. 1 is a front perspective view of a MIFI device showing my new design in a combined state, comprised of a front section and a rear section;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front perspective view of the MIFI device of FIG. 1 in a separated state in order to show aspects of the design not otherwise apparent;

FIG. 10 is a rear perspective view thereof; and,

FIG. 11 is another front elevational view of the MIFI device of FIG. 1 showing only the rear section in order to show aspects of the design not otherwise apparent.
